[57] CLAIM

The ornamental design for circular container, as shown and described.

DESCRIPTION

FIG. 1 is a perspective view of a circular container showing my new design;
 FIG. 2 is a top plan view thereof;
 FIG. 3 is a front elevational view thereof;
 FIG. 4 is a bottom plan view;
 FIG. 5 is a right side elevational view, the left side elevational view being a mirror image thereof;
 FIG. 6 is a rear elevational view;
 FIG. 7 is a plan view of the inside top of the circular container in an open condition;
 FIG. 8 is a plan view of the inside bottom of the circular container in an open condition;
 FIG. 9 is a perspective view of a second embodiment of a circular container incorporating my new design;
 FIG. 10 is a top plan view thereof;
 FIG. 11 is a front elevational view thereof;
 FIG. 12 is a bottom plan view;

FIG. 13 is a right side elevational view, the left side elevational view being a mirror image thereof;
FIG. 14 is a plan view of the inside top of the circular container in an open condition;
FIG. 15 is a plan view of the inside bottom of the circular container in an open condition;
FIG. 16 is a perspective view of a third embodiment of a circular container incorporating my new design;
FIG. 17 is a top plan view thereof;
FIG. 18 is a front elevational view thereof;
FIG. 19 is a bottom plan view;
FIG. 20 is a right side elevational view, the left side elevational view being a mirror image thereof;
FIG. 21 is a plan view of the inside top of the circular container in an open condition;
FIG. 22 is a plan view of the inside bottom of the circular container in an open condition;
FIG. 23 is a perspective view of a fourth embodiment of a circular container incorporating my new design;
FIG. 24 is a top plan view thereof;
FIG. 25 is a front elevational view thereof;
FIG. 26 is a bottom plan view;
FIG. 27 is a right side elevational view, the left side elevational view being a mirror image thereof;
FIG. 28 is a rear elevational view;
FIG. 29 is a plan view of the inside top of the circular container in an open condition;
FIG. 30 is a plan view of the inside bottom of the circular container in an open condition;

FIG. 31 is a perspective view of a fifth embodiment of a circular container incorporating my new design;
FIG. 32 is a top plan view thereof;
FIG. 33 is a front elevational view thereof;
FIG. 34 is a bottom plan view;
FIG. 35 is a right side elevational view, the left side elevational view being a mirror image thereof;
FIG. 36 is a rear elevational view;
FIG. 37 is a plan view of the inside top of the circular container in an open condition;
FIG. 38 is a plan view of the inside bottom of the circular container in an open condition;
FIG. 39 is a perspective view of a sixth embodiment of a circular container incorporating my new design;
FIG. 40 is a top plan view thereof;
FIG. 41 is a front elevational view thereof;
FIG. 42 is a bottom plan view;
FIG. 43 is a right side elevational view, the left side elevational view being a mirror image thereof;
FIG. 44 is a rear elevational view;
FIG. 45 is a plan view of the inside top of the circular container in an open condition; and,
FIG. 46 is a plan view of the inside bottom of the circular container in an open condition.
